UNITED STATES PATENT OFFICE.

ANDREW M. JAMISON, OF SPARTANBURG, SOUTH CAROLINA.

CIGAR PRESS.

Application filed March 1, 1923. Serial No. 622,087.

To all whom it may concern:

Be it known that I, ANDREW M. JAMISON, a citizen of the United States, residing at Spartanburg, in the county of Spartanburg and State of South Carolina, have invented certain new and useful Improvements in Cigar Presses, of which the following is a specification.

This invention relates to a cigar press designed for use in connection with the compressing of a bunch of cigars of a size for packing in a container, and has for its object to provide in a manner as hereinafter set forth, a press of such class whereby a wrapped bunch of cigars can be readily compressed, without injury to the wrapper or to the cigars, to the desired size to provide for the easy sliding of the compressed bunch from the press into a polygonal or cylindrical container.

A further object of the invention is to provide, in a manner as hereinafter set forth a press for the purpose referred to with means constituting a compressing element and whereby said element can be quickly swung to inoperative position so that convenient access can be had to the compressed bunch to enable the quick sliding of the latter from the press into a container.

Further objects of the invention are to provide in a manner as hereinafter set forth, a press for the purpose referred to, which is simple in its construction, strong, durable, compact, thoroughly efficient in its use, conveniently operated, readily set up and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts through the several views:

Figure 1 is a perspective view of a press in accordance with this invention, the compressing element being shown in operative position.

Figure 2 is a longitudinal sectional view of the press when employed in connection with the compressing of a bunch of cigars

in a polygonal shape, and further illustrating the compressing element thrown to inoperative position and also showing the container supported by the press and the wrapped bunch of cigars which is to be reduced for insertion into the container.

Figure 3 is a longitudinal sectional view with the press thrown open and further illustrating the compressed bunch of cigars partially inserted in the container supported by the press.

Figure 4 is a longitudinal sectional view, broken away, of the press showing the setting up thereof with forming elements for the purpose of compressing a bunch of cigars into cylindrical form.

Figure 5 is a front view of the press when employed for compressing a bunch of cigars into cylindrical form.

Figure 6 is a fragmentary view, in cross section, illustrating one of the forming members and the means for detachably securing it to the bottom of the body portion of the press.

A press in accordance with this invention can be employed for compressing a wrapped bunch of cigars into polygonal form, or in cylindrical form, and without breaking or damaging the wrapper of the bunch, or injuring the cigars, and Figures 1 to 3 of the drawings illustrate the adaptation of the press when compressing a wrapped bunch of cigars into polygonal form, and Figures 4 to 6 illustrate the adaptation of the press for use in connection with the compressing of a wrapped bunch of cigars into cylindrical form.

The press comprises a body portion formed of a bottom 1, and a pair of side walls 2, 3, which are of less length than the bottom 1. The side walls 2, 3, are mounted on the upper face of the bottom 1, are flush with the side edges of the bottom 1, as well as flush with the rear edge thereof. Coupling plates 4 are provided for fixedly securing the walls 2, 3, to the bottom 1, and the said plates 4 are secured to the bottom 1 and side walls 2, 3, by hold-fast devices 5.

The rear portion of the bottom 1, as indicated at 6, is of greater height than the forward portion of the bottom 1 as indicated at 7, and by this arrangement the bottom 1, intermediate its ends is formed with a transversely extending shoulder 8 which constitutes a stop for a purpose to be hereinafter referred to. The side walls 2, 3, are

5 mounted on that part of the bottom 1 of greater height, as well as projecting forwardly from said portion 6, so as to overhang the rear part of the portion 7 of the bottom 1, as indicated at 9. The inner face of the wall 2, as well as the wall 3, is provided with a vertically disposed shoulder 10, which is arranged in alignment with the shoulder 8, as well as associating with the shoulder 8 to provide a stop for a purpose to be hereinafter referred to. The shoulders 10 extend from the bottom to the top of the side walls 2, 3.

15 The body portion of the press further includes a back wall 11, which is hinged as at 12, to the rear end of the bottom 1, and when the back wall 11 is in normal position it is interposed between the side walls 2, 3, and rests upon the rear end of the bottom 1.

20 By setting up the body portion of the press in the manner as stated, it is formed with an open top and an open front, and that part 7 of the bottom 1, provides a support for a container 13, as shown in Figures 2 and 3, and 25 the container is positioned to extend between the side walls 2, 3, and is arrested by the shoulders 8 and 10, which constitute stops. When the container 13 is mounted in position, its open end is arranged in close proximity to the wrapped bunch of cigars 14, the latter is mounted in the body portion as shown in Figure 2.

30 The press further includes a compressing element which consists of a lever formed of a 35 rectangular body portion 15, having projecting from one end thereof a handle portion 16, and the latter when the compressing element is shifted to operative position, extends over the portion 7 of the bottom 1, as shown in 40 Figure 1. The rear end of the body portion 15 of the compressing element is hinged to the top of the back wall 11, as at 17, and when the compressing element is utilized for compressing the wrapped bunch 14, it operates 45 between the side walls 2, 3, of the body portion of the press.

50 The shoulders 8 and 10, which constitute stops, are employed in connection with a polygonal shaped container to receive a wrapped bunch which has been compressed into polygonal contour, but when the wrapped bunch is compressed into cylindrical contour for insertion into a cylindrical container the latter is positioned in a manner 55 to be presently referred to.

When the press is employed for compressing a wrapped bunch of cigars into cylindrical form for insertion into a cylindrical container, the body portion of the press has 60 mounted therein a pair of superposed former members 18, 19, and each of which consists of a rectangular block. The member 18 has its lower face formed with a convex pocket 20, and the member 19 has its upper face 65 formed with a concave pocket 21. When

the members 18 and 19 are mounted in the body portion of the press, the wall of the pocket 20 forms a continuation of the wall of the pocket 21, and the shape of the pockets 20, 21, is such that after the member 18 has been shifted relatively to the member 19, the wrapped bunch of cigars which is inclosed by the members 18, 19, will be compressed into cylindrical form. The member 18 is operated upon by the compressing element, 70 that is to say, the body portion 15 of said compressing element.

75 The member 18, as well as the member 19 is of a length equal to the length of the side wall 2, or the side wall 3, but the combined height of the members 18 and 19 is less than the height of either side of the body portion of the press. The member 18, as well as the member 19, has the wall of its recess at the forward end thereof rabbeted, as at 22, which provides a shoulder 23, and the latter constitutes a stop for the open end of the container. When the container is mounted in position with respect to the press, it is inserted in the forward ends of the members 18, 19, that is 80 to say, on the rabbeted portion 22 and against the shoulder 23, so that after the wrapped bunch has been compressed to the desired size, it can be quickly slid into the container.

85 When the wrapped bunch has been compressed to polygonal form, or to cylindrical form, the rear wall 11 and compressing element are swung rearwardly to the position shown in Figure 3, and which enables the operator to quickly slide the compressed 90 wrapped bunch into the container.

95 The member 19 is provided with a pair of holding pins 24 which engage in openings 25, provided in the bottom 1 of the press, whereby the member 19 is detachably secured in 100 position.

105 In Figure 2 of the drawings, the wrapped bunch is illustrated prior to the compression thereof and its insertion into the container, and in Figure 3 of the drawings the wrapped bunch is shown compressed and partially inserted in the container.

110 From the foregoing description taken in connection with the accompanying drawings, a press is set up whereby wrapped bunches of cigars can be quickly compressed to the desired shape and easily inserted in the container, and although the preferred construction of the press is as described and claimed, yet it is to be understood that changes in the 115 details of construction can be had which will fall within the light of the invention as claimed.

120 What I claim is:—

125 1. A cigar press for the purpose set forth comprising a body portion open at its front and top and provided with a back wall hinged to the rear end of the bottom of the body portion, and a compressing element hinged at its rear end to the top of the back

wall and operating in the top of said body portion when said element is shifted to operative position.

2. A cigar press for the purpose set forth comprising a body portion open at its front and top and provided with a back wall hinged to the rear end of the bottom of the body portion, and a compressing element hinged at its rear end to the top of the back wall and operating in the top of said body portion when said element is shifted to operative position, the bottom of said body portion extended from the front of the sides of said body portion to provide a support for a container.

3. A cigar press for the purpose set forth comprising a body portion open at its front and top and provided with a back wall hinged to the rear end of the bottom of the body portion, and a compressing element hinged at its rear end to the top of the back wall and operating in the top of said body portion when said element is shifted to operative position, said element including a handle portion projecting forwardly from the sides of said body portion when said element is in operative position.

4. A cigar press for the purpose set forth comprising a body portion open at its front and top and provided with a back wall hinged to the rear end of the bottom of the body portion, and a compressing element hinged at its rear end to the top of the back wall and operating in the top of said body portion when said element is shifted to operative position, the bottom of said body portion extended from the front of the sides of said body portion to provide a support for a container, and said element including a handle portion extending over said support when said element is swung to operative position.

5. A cigar press for the purpose set forth comprising a body portion open at its front and top and provided with a back wall hinged to the rear end of the bottom of the body portion, and a compressing element hinged at its rear end to the top of the back wall and operating in the top of said body portion when said element is shifted to operative position, the bottom of said body portion extended from the front of the sides of said body portion to provide a support for a container, and means to provide a stop for one end of the container when mounted on said support.

6. A cigar press for the purpose set forth comprising a body portion open at its front and top and provided with a back wall hinged to the rear end of the bottom of the body portion, a compressing element hinged at its rear end to the top of the back wall and operating in the top of said body portion when said element is shifted to operative position, the bottom of said body por-

tion extended from the front of the sides of said body portion to provide a support for a container, and said element including a handle portion extending over said support when said element is swung to operative position, and means to provide a stop for one end of the container when mounted on said support.

7. A cigar press for the purpose set forth comprising a body portion open at its front and top and provided with a back wall hinged to the rear end of the bottom of the body portion, a compressing element hinged at its rear end to the top of the back wall and operating in the top of said body portion when said element is shifted to operative position, and oppositely disposed forming members arranged in said body portion, said members having their opposed faces providing a cylindrical opening.

8. A cigar press for the purpose set forth comprising a body portion open at its front and top and provided with a back wall hinged to the rear end of the bottom of the body portion, a compressing element hinged at its rear end to the top of the back wall and operating in the top of said body portion when said element is shifted to operative position, said element including a handle portion projecting forwardly from the sides of said body portion when said element is in operative position, and oppositely disposed forming members arranged in said body portion, said members having their opposed faces providing a cylindrical opening.

9. A cigar press for the purpose set forth comprising a body portion open at its front and top and provided with a back wall hinged to the rear end of the bottom of the body portion, a compressing element hinged at its rear end to the top of the back wall and operating in the top of said body portion when said element is shifted to operative position, and oppositely disposed forming members arranged in said body portion, said members having their opposed faces providing a cylindrical opening, one of said members having means engaging in said body portion for detachably connecting said member therewith.

10. A cigar press for the purpose set forth comprising a body portion open at its front and top and provided with a back wall hinged to the rear end of the bottom of the body portion, a compressing element hinged at its rear end to the top of the back wall and operating in the top of said body portion when said element is shifted to operative position, said element including a handle portion projecting forwardly from the sides of said body portion when said element is in operative position, and oppositely disposed forming members arranged in said body portion, said members having their

opposed faces providing a cylindrical opening, one of said members having means engaging in said body portion for detachably connecting said member therewith.

11. A cigar press for the purpose set forth comprising a body portion consisting of a bottom, a pair of side walls and a back wall, said side walls arranged at the rear of and of less length than said bottom whereby the latter will project forwardly

from the side walls, said back wall hinged to the rear end of said bottom and extending between the side walls when in normal position, and a compressing element hinged to the top of the back wall and operating ¹⁵ between and projecting forwardly from said side walls.

In testimony whereof, I affix my signature hereto.

ANDREW M. JAMISON.
